(57) **CLAIM**

I claim the ornamental design for a dual hull folding boat, as shown and described.

DESCRIPTION

The present application claims priority to co-pending U.S. Utility Patent application Ser. No. 16/048,177 with primary inventor Roland Heersink, entitled “Multiple Hull Folding Boat” and filed on Jul. 27, 2018.

FIG. 1 is a top left rear perspective view of the dual hull folding boat;

FIG. 2 is a bottom left front perspective view of FIG. 1.

FIG. 3 is the top plan view of FIG. 1.

FIG. 4 is the bottom plan view of FIG. 1.

FIG. 5 is a top left rear perspective view of the dual hull folding boat, showing an additional structural element in the rear portion of the boat;

FIG. 6 is a bottom left front perspective view of FIG. 5.

FIG. 7 is the top plan view of FIG. 5; and,

FIG. 8 is the bottom plan view of FIG. 5.

My design for a dual hull folding boat is characterized by the ability to disassemble and fold flat, after use as a boat in any body of water.
